John L. Dunnock, Baltimore, Md., assignor, by mesne assignments, to Max Factor & Company,
Hollywood, Calif.

Application September 21, 1937, Serial No. 71,706

Term of patent 7 years

To all whom it may concern:

Be it known that I, John L. Dunnock, a citizen of the United States, residing at Baltimore city and State of Maryland, have invented a new, original, and ornamental Design for a Bottle, of which the following is a specification, reference being had to the accompanying drawing, forming part thereof:

I claim:

The ornamental design for a bottle substantially as shown.

JOHN L. DUNNOCK.
